UNITED STATES PATENT OFFICE.

HENRY C. GLINSMANN, OF BAYONNE, NEW JERSEY

WASHING-MACHINE.

SPECIFICATION forming part of Letters Patent No. 365,594, dated June 28, 1887.

Application filed October 11, 1886. Serial No. 215,816. (No model.)

To all whom it may concern:

Be it known that I, HENRY C. GLINSMANN, of Bayonne, Hudson county, State of New Jersey, have invented a new and Improved 5 Washing - Machine, of which the following specification is a full, clear, and exact description.

This invention relates to a washing-machine of simple construction; and it consists in the 10 various elements of improvement, hereinafter more fully pointed out in the claims.

In the accompanying drawings, Figure 1 is an end view of my improved washing-machine. Fig. 2 is a vertical transverse section 15 of the same on the line $x-x$, Fig. 4. Fig. 3 is a cross-section of the suds-box on line $y-y$, Fig. 4. Fig. 4 is a top view of the machine; Fig. 5, a side view of the oscillating frame, showing the roller in section. Figs. 6 and 7 are 20 detail views showing the handle-socket and handle.

The letter a represents the cast-metal frame supported on legs and inclosing the suds-box b , made of sheet metal.

25 c is the dasher-roller, journaled at its ends in two levers, d , that are connected by a cross-bar, e , the whole constituting an oscillating frame, which is pivoted within the suds-box by trunnions f , projecting inwardly from the 30 suds-box and engaging slots g , formed in levers d .

Beneath the cross-bar e the levers d are connected by a second cross-bar, h , having two (more or less) upwardly-projecting perforated 35 arms, i , that encircle the upper cross-bar, e . Between arms i sleeves j are slipped over the cross-bar e , and in this way a very strong and convenient hand-piece for oscillating the levers d and roller c is produced. The arms i 40 not only serve to strengthen the cross-bar e , that has to bear the pressure from the hands, but they also serve as braces for the entire oscillating frame, which must be very rigidly joined on top, inasmuch as the lower ends of 45 the levers d , being disconnected, would otherwise be apt to spread apart.

To the outer side of each lever d there is attached a tube, k , into which is fitted a rubber plug, l , projecting out of both of the open ends 50 of the tube. This plug constitutes a buffer to limit the backward and forward motion of the frame. The buffer is adapted to come in contact with lugs or stops m , projecting upwardly from the frame a , and having inclined bearing-faces, as shown.

The suds-box b is made with a corrugated concave bottom, o , Fig. 2, which is joined to the front and rear faces, $n n$, of the suds-box. These faces are not straight up and down, as usual, but are straight on top only, while they 60 are bulged outwardly near their lower ends, so as to form concave section n' , which merge into the bottom, as shown. These concave sections are corrugated to correspond with bottom o .

p is the splash-board, adapted to support a wringer and made of trough shape, as shown, so as to catch the drippings and guide them into the suds-box. The cover q is supported upon the lower edge of the splash-board and 70 upon a bead on the opposite side of the suds-box.

r is one of the handles of the machine. This handle has inwardly-projecting lugs, as usual, fitting into sockets s , cast in the frame a , such 75 sockets being open at their back. The sockets are formed at opposite sides of a central bar, a' , forming part of casting a . This bar is made of tapering shape, being at its greatest width at the point where it is provided with 80 the sockets. To attach the handle r to the frame a , such handle is slipped over the lower narrow end of bar a' , and is then passed upward until its lugs engage sockets s . Thus the handles may be applied even though the 85 suds-box is in position. The machine is operated, in the usual way, by rocking its oscillating frame backward and forward.

I claim as my invention—

1. The combination of frame a , suds-box b , 90 levers d , cross-bar e , and roller c , with the inclined lugs m , secured to frame a , and with the tubes k and plugs l , secured to levers d , substantially as specified.

2. The combination of frame a , having tapering bar a' and sockets s , with the handle r , 95 adapted to engage said sockets, substantially as specified.

3. The combination, with a tub or suds-box having journal-bearings, as described, of a reciprocating rubber composed of slotted levers, a transverse bar connecting the upper ends thereof, spools arranged on the said bar, and a lower transverse bar having short branches provided with eyes to receive the 100 said upper bar, substantially as specified.

HENRY C. GLINSMANN.
